ATTORNEY.

UNITED STATES PATENT OFFICE.

FRANZ AUGUST GERHARD FÖRSTER, OF LOBAU, GERMANY.

PIANO HAVING QUARTER TONES.

Application filed January 13, 1925, Serial No. 2,084, and in Germany March 17, 1924.

This invention relates to a novel piano having quarter tones and consists essentially therein that the key-board is composed of three full key-boards of which the lower 5 key-board contains the full tones, while the middle key-board is somewhat displaced with regard to the lower key-board and contains the quarter tones, the upper key-board representing a short repetition of the lower 10 key-board, the keys of which are in mechanical connection with the keys of the lower key-board.

This invention consists furthermore in the employment of a double sounding board, 15 which by special means is so compensated that the vibrations of the individual boards are brought into unison.

With quarter tone keyed instruments it is known to employ key-boards, in which 20 the quarter tones are inserted between the half tone keys by having the width of all keys made of a reduced size. A key-board of this kind, which is obtained from a normal key-board by vertically sub-dividing 25 the same is difficult to play on account of the small width of all keys.

Furthermore, there are key-boards in which the quarter tone keys are positioned in a plurality of closed strips placed horizontally between the keys of the half tones. 30 By this arrangement the vertical playing depth of all rows of keys is diminished in such a way, that with hands of medium size it is not possible to strike a greater accord upon one strip of keys. If an attempt were made to reach several tones of the same accord upon a row of keys which is placed further in the rear, it would be 35 found that the playing is unsatisfactory because the ordinary hand could not bridge the intermediate row of keys. Consequently it becomes necessary to discard altogether the system of a plurality of rows of keys with a small depth of play and to 40 dispose the rows of keys so that the front row will comprise in the usual manner the full and the half tones, while a second row is placed somewhat higher than and in the rear of said front row, the second row containing the quarter tones and a third row of 45 keys disposed still higher and in the rear of said second row, said third row representing a shortened duplicate of the lower first row of keys.

50 From reasons which are connected with the playing of the instrument, it will be

desirable to always place the rear playing surface higher than the front surface to an extent as would correspond in normal key-boards to the difference in the height between white and black keys. By this it will be necessary to reduce as much as possible the difference in height within the same row of keys, which contains all tones in even width and in chromatic sequence. 60 65

Since it will frequently be impossible to move the inner fingers of the hand from the middle row of keys for the quarter tones towards the lower row containing the normal keys, there is further arranged a 70 third strip of keys in the rear and above the strip of the keys for the quarter tones, whose keys may be rigidly connected with the appertaining lower normal keys. In this case, the connections will pass through 75 the intermediate spaces of the strip of keys for the quarter tones and may for instance consist of two strong pins of iron wire and a screw for the tightening of the same. The wire pins are provided at their upper 80 ends with a right-hand thread and at their lower ends with a left-hand thread and are furthermore provided with a proper cut 85 permitting a regulation by means of a screw driver. The keys may be constructed as levers and brought in operating connection with the appertaining lower normal keys or their mechanisms. The quarter tone keys, which are constructed as levers with a single arm, are positioned in the rear with 90 in caps, while the lower keys for the full tones and the half tones are positioned upon scale-beams and bent at their front end in upward direction in order to attain the necessary difference in the height 95 between the two rows of keys. All keys are towards above shaped obliquely, such as is the case in the upper tones of normal instruments. 100

105 Since the key-board, in which the white and black keys are of even length, would offer to the eye a somewhat confusing picture, it will be necessary to retain in some form the enlargement of the white keys which is present in the usual key-boards in front of the black keys. In the rear row of keys for reasons connected with the playing this will not be desirable, it will, however be possible at the front and middle row of keys. In this case, for technical reasons, 110 the usual width of the strip of the keys is somewhat reduced. 113

The key-board is shown diagrammatically in a top-view in Fig. 1 and in Fig. 2 in a side view. Fig. 3 shows a modified form of the piano according to this invention employing a double sounding board and means for compensating the sound differences of the two parts thereof. In the first row the keys 1 will give the full tones and 2 the half tones and upon the middle key-board the keys 3 and 4 will represent the quarter tones, while upon the upper key-board the keys 5 and 6 will correspond to the lowermost keys 1 and 2.

In this key-board there have been used in every case two acoustically independent sounding boards, of which one serves for the transmission of the full and half tones, the other for the transmission of the quarter tones to the audience. It is known, that in spite of most careful manufacture two instruments will always be different from each other in their individual tones, a feature, which for the present case is most undesirable. It will therefore be necessary to bring the vibrating parts, that is to say the sounding boards, in intimate mechanical connection with each other.

The most suitable basis for a construction of this kind is found in the double sounding board, in which, as known, the two individual boards are connected by having the vibrations of the upper bridge transmitted through a third bridge positioned between both sounding boards upon the lower board and vice versa. The vibrations of the lower bridge will also be transmitted upon the upper board.

Double sounding boards have heretofore been used in many variations with the purpose to increase the strength of the tone of a normal piano. Since, however, the sounding board represents a mass expanding in the manner of a surface, and accordingly will be set into forced vibrations by an impulse of fixed strength, an augmentation of this mass with the strength of the impulse remaining the same, will never cause to augment the vibrations in its entirety, but the exciting impulse will distribute itself upon both surfaces, so that they will swing with one half of the energy. The rare use of double sounding boards in actual practice is a proof for this.

The present invention, which consists in the employment of a so-called double sounding board for the construction of a grand

piano with quarter tones, has therefore not for its purpose to increase the strength of the tone, but to bring about a compensation of the normally occurring differences in the sounds given by the two sounding boards. This is attained by exciting both sounding boards uniformly during the striking of a half tone as well as of a quarter tone.

In Fig. 3, 7 represents the sounding board for the quarter tones and 8 the sounding board for the half tones, the arch of the latter and arrangement of the ribs being opposed to the upper sounding board. 9 and 10 designate the appertaining lateral bridges while 11 represents the intermediate bridge effecting the transmission, said bridge being eventually provided with openings. 12 and 13 designate the two iron frames, which carry the strings of the instrument, either of said frames representing the reflected image of the other.

I claim:

1. In a quarter tone piano the combination of three full key-boards arranged one above the other, the lower of said key-boards containing the full tones and the semitones, the middle being somewhat displaced against the lower board and containing the quarter tones, and the upper key-board representing a short repetition of the lower key-board, with mechanical means for interconnecting the keys of the upper with those of the lower board.

2. A quarter tone piano comprising three full key-boards arranged one above the other, the lower of said key-boards containing the full tones and the semitones, the middle board being displaced against the lower board and containing the quarter tones, while the upper board represents a short repetition of the lower key-board, said two upper key-boards having all keys of even length and the full tone keys of the lowermost key board projecting only relatively little above the keys, for the semitones, and means for interconnecting the keys of the key-board with those of the lower key-board.

3. A quarter tone piano according to claim 1, having two sounding boards, which are connected by a bridge for compensating the tone differences of the two sounding boards.

In testimony whereof I affixed my signature.

FRANZ AUGUST GERHARD FÖRSTER.
